UNITED STATES PATENT OFFICE.

ALEXANDER MCPHERSON, OF WINDSOR, NOVA SCOTIA, CANADA, ASSIGNOR OF
ONE-HALF TO WILLIAM O'NEIL, OF ST. JOHN, NEW BRUNSWICK, CANADA.

TREE-SAWING MACHINE.

1,305,479.

Specification of Letters Patent.

Patented June 3, 1919.

Application filed February 17, 1917. Serial No. 149,356.

To all whom it may concern:

Be it known that I, ALEXANDER MCPHERSON, a subject of the King of England, residing at Windsor, in the county of Hants, 5 in the Province of Nova Scotia, in the Dominion of Canada, have invented a new and useful Tree-Sawing Machine, of which the following is a specification.

My invention relates to labor saving machines used in the manufacture of forest growth into merchantable lumber and the object of my invention is to provide a machine in which the sources of power can be readily and expeditiously employed in felling forest trees and cutting them into lengths required in the ordinary courses of manufacturing.

I attain this object by the mechanism illustrated in the accompanying drawing in 20 which Figure 1. is a compressor and its receiver for the purpose of supplying compressed air when air is used as the direct motive power. Fig. 2. is a plan of the machine as used when cutting the fallen trees 25 into suitable lengths, parts being omitted. Fig. 3. is a plan of the machine turned 45° from the location shown in Fig. 2 and in the position required for sawing down standing trees. Fig. 4. is an enlarged portion of the 30 supporting bar. Fig. 5. is an elevation of the telescopic legs which are attached to and support one end of the supporting bar. Fig. 6. is a section of Fig. 3 on line a c. Fig. 7. is a section of Fig. 3 on line c b. Fig. 8. is a section of Fig. 3 on the lines o o 35 and c c showing the saw guide.

Similar letters refer to similar parts throughout the several views.

a is the supporting bar to one end of 40 which the telescopic legs b b are attached, which legs are for the purpose of regulating the height of the supporting bar from the ground. c.c.c are short spear points which are rigidly attached to the opposite end of 45 the supporting bar and by being forced partially into the tree to be operated on at the desired height by means of a flexible binder d which is secured at one end in any manner to a collar D and which is fastened at its 50 opposite end to the said collar by means of an eye bolt f. The collar D is mounted on the end of the bar a and is provided with opposite extensions e to which the ends of the binder d are connected. g is a cylinder

which is adapted to the use of either compressed air or steam, it is carried by the pinch band i on which it is revoluble in the plane of its axis being held in place by the bolt j. The pinch band i in turn is carried by the supporting bar a on which by means of the bolt and nut k the cylinder with its attachments can readily be adjusted to any required angle, the flexible hose l which serves to conduct the compressed air or steam to the said cylinder readily accommodating itself to any angle. m is a piston rod which carries the piston head n, it passes direct through the cylinder projecting at each end. o o are rotary valve chests the valves of which are moved by the operating mechanism comprising an operating member p consisting of a lateral extension of the cross heads r and arranged between projections p¹ which are adjustably mounted on a longitudinal rod p¹¹. The valves o are provided with depending crank arms p¹¹¹ to which the longitudinal rod is connected and the lateral extension p, which is carried by the piston rod, alternately engages the projections p¹ of the said longitudinal rod p¹¹ 80 and shifts the valves o to control the admission of fluid pressure to, and the exhaust of the same from, the cylinder. r is a cross head at the end of the piston rod m to which the cut off saw B is bolted. s s is a bow rigidly secured to the cylinder chiefly for the purpose of carrying the saw guide t. u is a bow secured to the bow s for the purpose of regulating the feed and for convenience in handling the saw. v is a valve for the 85 purpose of regulating the supply of the motive power and stroke speed of the saw.

I am aware that cylinders adapted to the use of steam or compressed air having automatically operated rotary valves are not new and I therefore do not broadly claim such as my invention, but what I do claim and desire to secure by patent is:

1. A tree sawing machine comprising a longitudinal bar provided at one end with a collar having terminal tree engaging means and lateral extensions, flexible means connected with the extensions for securing the adjacent end of a bar to a tree, means for adjustably supporting the other end of the bar, and a sawing machine extending longitudinally of the bar and pivotally supported on the bar intermediate of the ends 100 105

thereof and adjustable along the bar between the collar and the said adjustable supporting means.

2. In a tree sawing machine, a longitudinal supporting bar provided at one end with means for attaching it to a tree, means for adjustably supporting the other end of the bar, a cylinder pivoted on the bar intermediate of the ends thereof and adjustable 10 along the same between the attached end of the bar and the adjustable supporting means, a frame carried by the cylinder having a saw guide at its outer end, a piston operable in the cylinder, a piston rod connected with the piston and supported at its outer end by the frame, and a saw attached 15 to the outer end of the piston rod and guided in its movements by the said saw guide.
3. A tree sawing machine comprising a 20 longitudinal supporting bar having a tree engaging point at one end and provided at the other end with a longitudinal pivot, legs connected at their upper ends with the bar by the said pivot and adjustably supporting 25 the said bar, a cylinder provided with means for adjustably mounting it upon the bar and movable along the same to arrange it different distances from the tree engaging point, a piston operating in the cylinder, and 30 a saw connected with and actuated by the piston.

Copies of this patent may be obtained for five cents each, by addressing the "Commissioner of Patents, Washington, D. C."

4. A tree sawing machine comprising a longitudinal supporting bar having a tree engaging point at one end and provided at the other end with a longitudinal pivot, legs 35 connected at their upper ends with the bar by the said pivot and adjustably supporting the said bar, a cylinder, a clamp adjustably embracing the bar and provided with means for pivotally connecting the cylinder to it 40 and having a longitudinal and rotary adjustment with respect to the said bar, a piston operating in the cylinder, and a saw connected with and actuated by the piston.

5. A tree sawing machine comprising a 45 longitudinal supporting bar provided at one end with tree engaging means, legs connected with the other end of the bar for supporting the same, a cylinder adjustably mounted on the bar and movable longitudinally of the same, a yoke or bow carried by the cylinder and extending forwardly therefrom and provided at the front end with a transverse guide, a piston operating in the cylinder and a saw connected with and actuated by the piston and arranged in the 50 said transverse guide.

ALEXANDER McPHERSON.
